O. O. KOLSTAD.

BOTTLE.

APPLICATION FILED FEB. 16, 1916.

Patented Nov. 28, 1916.

UNITED STATES PATENT OFFICE.

OLE O. KOLSTAD, OF DULUTH, MINNESOTA.

BOTTLE.

1,206,335.

Specification of Letters Patent. Patented Nov. 28, 1916.

Application filed February 16, 1916. Serial No. 78,746.

To all whom it may concern:

Be it known that I, OLE O. KOLSTAD, a citizen of the United States, residing at Duluth, in the county of St. Louis and 5 State of Minnesota, have invented new and useful Improvements in Bottles, of which the following is a specification.

This invention relates to bottles especially adapted to be used for containing poisons 10 and similar dangerous fluids and it consists in the novel features hereinafter described and claimed.

An object of the invention is to provide a bottle having a cork located interiorly 15 of the neck thereof, with means for forcing the cork into the neck when the bottle is turned to an inverted position thereby preventing the flow of liquid from the bottle.

With this object in view the bottle includes a body having a neck integrally joined therewith, the said neck at a point 20 between its ends being swelled laterally, there being provided at the inner end of the neck a seat upon which a ball normally rests when the bottle is in upright position. A cork is located in the swelled portion of 25 the neck between the said ball and the outlet end of the neck. Consequently when the bottle is turned to an inverted position the ball holds against the cork and forces the same into the neck whereby the flow of liquid from the bottle is prevented. In order to pour the liquid from the bottle it is necessary to insert an implement in 30 the neck whereby the cork is displaced from its position at the outlet portion of the neck and the liquid may flow from the bottle. By this provision it is comparatively safe to use the bottle as a poison container for the reason that in order to pour the liquid from the bottle it is necessary to use an implement to unseat the cork from the inner portion of the neck. Therefore, 35 persons who are unfamiliar with the operation of the bottle cannot get at the contents and especially as this is the case where the bottle is exposed to the use of children who might without the provision hereinbefore described pour and consume the contents of the bottle with disastrous effects.

In the accompanying drawing:—Figure 1 is a vertical sectional view of the bottle. Fig. 2 is a similar view showing the bottle

in an inverted position. Fig. 3 is a transverse sectional view cut on the line *a—a* of 55 Fig. 1.

The bottle includes a body 1 which may be of any shape or design and a neck 2 is integrally joined therewith in the usual manner. The neck 2 is provided at its 60 point of juncture with the body 1 with a seat 3. The neck 2 between its ends is swelled laterally as at 4. The outlet end of the neck 2 is constructed as at 5. A ball 6 of glass or other suitable material is located 65 in the swelled portion 4 of the neck and when the bottle is in upright position the said ball rests upon the seat 3 and closes the outlet of the body 1 and protects the contents thereof against the evaporation, dust, 70 etc. A cork 7 of cork bark, wood or other material is also located in the swelled portion 4 of the neck 2 and is between the ball 6 and the constricted portion 5 of the said neck.

If desired the cork 7 may be in the form 75 of a hollow rubber body and in fact the material of which the said cork is composed is immaterial. When the bottle is in an upright position as hereinbefore stated, the ball 6 rests upon the seat 3 while the cork 80 7 is in the swelled portion of the neck above the ball. When the bottle is turned to an inverted position to pour the contents thereof the ball 6 moves away from the seat and comes in contact with the inner end of 85 the cork 7 and forces the same into the constricted outlet 5 of the neck 2. Thus the passage way of the liquid from the body 1 through the neck 2 is interrupted and in order to secure a flow of the liquid from the 90 neck 2 it is necessary to insert a needle or other long narrow implement into the outlet end of the neck and push the cork 7 away from the inner end of the constricted portion 5 of the said neck. When this is 95 done the liquid may flow by the ball and the cork and out at the delivery end of the neck 2. By such an arrangement it is impossible for a person who is unable to read a label or who is unfamiliar with the operation of the bottle to pour the contents therefrom. In view of the fact that it is necessary to insert an implement into the bottle neck to move the cork from the constricted end to secure the flow of the liquid, hence, 100 105 the bottle may be safely kept on a shelf with

other bottles, and in event that the bottle should fall in the hands of children, they cannot gain access to the contents for the reason that they would be unfamiliar with 5 the manner of removing the cork from the outlet end of the neck.

When a suitable amount of the liquid has been poured from the bottle by one familiar with the operation and the bottle is returned 10 to an upright position the ball 6 by gravity engages the seat 3 and seals the body 1 thereby protecting its contents against evaporation and the entrance of dust or other foreign substance into the body through the 15 neck.

From the foregoing description taken in conjunction with the accompanying drawing, it will be seen that a bottle of simple structural arrangement is provided and that 20 the same effectually protects its contents while not in use and the contents are prevented from being poured from the same

by persons unfamiliar with the operation of the elements of the structure.

Having described the invention what is 25 claimed is:

A bottle comprising a body having a neck joined therewith, there being provided at the point of juncture between the neck and the body a seat, the neck having between its 30 ends a swelled portion and a constricted outlet end, a ball located completely within the swelled portion of the neck and adapted to engage the seat, and a cork located in the swelled portion of the neck and adapted to engage the constricted end thereof when the bottle is turned to an inverted position.

In testimony whereof I affix my signature in presence of two witnesses.

OLE O. KOLSTAD.

Witnesses:
